CLAIM

The ornamental design for a belt-like retainer for holding a flexible bag in a container, as shown and described.

DESCRIPTION

FIG. 1 shows a perspective view of the present invention; FIG. 2 shows a side view of the present invention in an alternate position of use; and,

FIG. 3 shows a side view of the claimed design; and, FIG. 4 shows a view from the other side of the claimed design.

The broken line showing of a flexible bag and container is for illustrative purposes only and forms no part of the claimed design.
